UNITED STATES PATENT OFFICE.

ISAAC E. PALMER, OF MIDDLETOWN, CONNECTICUT.

DESIGN FOR A HAMMOCK.

SPECIFICATION forming part of Design No. 25,110, dated January 28, 1896.

Application filed December 21, 1895. Serial No. 572,927. Term of patent 14 years.

To all whom it may concern:

Be it known that I, ISAAC E. PALMER, of Middletown, in the county of Middlesex and State of Connecticut, have invented and produced a new and original Design for Hammocks, of which the following is a specification, reference being had to the accompanying drawing, forming a part thereof.

The leading feature of my design consists in a hammock having pronounced stripes consisting of connected scrolls along its opposite edges.

The accompanying drawing represents two pronounced stripes consisting of connected

scrolls along each of the opposite edges of the hammock, one along each of the opposite edges of the body portion proper and one along each of the valance portions.

The body portion of the hammock intermediate of the valances is denoted by A, the valances are denoted by $a a'$ and the stripes by B.

What I claim is—

The design for a hammock substantially as herein shown and described.

ISAAC E. PALMER.
